UNITED STATES PATENT OFFICE.

WILLIAM R. ROSE, OF WASHINGTON, DISTRICT OF COLUMBIA.

METAL SHEATHING FOR FIRE-WALLS.

No. 818,122.

Specification of Letters Patent.

Patented April 17, 1906.

Application filed December 16, 1905. Serial No. 292,064.

To all whom it may concern:

Be it known that I, WILLIAM R. ROSE, a citizen of the United States, residing at Washington, in the District of Columbia, have invented certain new and useful Improvements in Metal Sheathing for Fire-Walls, of which the following is a specification.

My invention relates to metal sheathing or covering for that portion of the party or fire wall projecting above the roofs of buildings.

It is desirable and is now generally the practice to sheath entirely with metal such portion of the wall; and it is the object of the present invention to provide a sheathing that may be applied expeditiously, is economical of material, and obviates all difficulty arising from the settling of new building construction.

In the embodiment of my invention as herein described, and illustrated in the drawings forming a part of this specification, I have shown the device in its application to a building construction in which what is known in the art as a "slag" roof is employed, though it is manifest that the invention is applicable in conjunction with other forms of roofing.

Referring to the drawings, Figure 1 is a sectional perspective view of a roof and fire-wall provided with my improved sheathing.

Fig. 2 is a perspective view showing the parts comprising my improvement in their relative positions, but in detached relation. Fig. 3 is a sectional view of the various parts of the sheathing in associated relation and with the roofing material applied.

In the figures, 1 designates the fire-wall, and 2 the roof.

3 is a layer of tar paper or felt usually employed as a primary covering for the roof in constructions of the character referred to.

4 is a sheet-metal covering or flashing for the side wall, having a flanged portion 5 lying upon the roof and preferably over the tar paper, where it is secured by nailing or otherwise. The free end of the flashing is terminated a short distance below the top of the wall for the purpose hereinafter stated.

6 is a strip of sheet metal of suitable dimensions to cover the top of the wall and permit of being bent over the sides thereof to form depending flanges 7, overlapping the free edge of the flashing. Slits or perforations 8 are formed at suitable intervals in the sheet-metal top cover, preferably near or at the bend in the metal.

9 designates flexible sheet-metal cleats of suitable length to be nailed to the roof and extend along the roof and up the wall beneath the flashing and flanged portion of the top cover to and through the slits therein, 6, where they are secured by being bent over, as shown. The engaging parts are then soldered to render the same secure and watertight. The method of securing the cleats to the cap-piece herein shown has been found 6, most satisfactory, though manifestly other means within the scope of my invention may be employed.

10 designates slag or other roofing material applied to the roof and over the portion 7, of the flashing lying thereon.

The cap-piece having been placed in position, the cleats are nailed to the roof and bent to conform to the angle of the roof and the wall. They are then passed through the slits 75 in the top cover. The flashing, also bent to conform to the angle of the roof and wall, is then placed in position. Then the projecting edge of the top cover is bent over upon the flashing and the protruding end of the cleats 80 hammered down. The slag or roofing material proper is then applied over the roof and portion of the flashing lying thereon and filled up close to the wall.

In the settling of new buildings caused by 85 seasoning of the timber, drying of green mortar, weight of the roof, and other causes there is more or less relative displacement of the roof and fire-wall. My wall-covering being made in two pieces free to move with the parts to 90 which they are secured and relatively to each other, the buckling and tearing of the parts is obviated. The flashing being secured only to the roof is free to move up or down beneath the flanged portion of the top cover 95 should there be any movement of the wall or roof. The metal cleats being secured to both the wall-cover and the roof, it is necessary so to construct and apply the cleats that upon the settling of the roof they will not be 100 torn from their fastenings. By constructing the cleats of flexible metal and securing them to the roof at a point removed from the wall upon the settling of the roof relatively to the wall, which is the usual occurrence, the cleats 105 will open out at the bend, thus relieving the strain upon their fastenings. In practice it has been found that the slight movement of the flashing and bending out of the cleats does not materially affect the efficiency of the 110

roof - covering, though there may be some slight displacement of the roofing material lying adjacent the wall.

What I claim is—

- 5 1. A metal sheathing for fire-walls comprising a flashing secured to the roof and having a free edge terminating below the top of the wall, a top cover for the wall having depending flanges overlapping the free edge of the flashing, flexible metal cleats secured to the top cover, extending beneath the flanged portion thereof and the flashing, and secured to the roof at points removed from the wall, and
- 10 2. In building construction, a fire-wall, a flashing secured to the roof and having a free
- 15 edge terminating below the top of the wall, a top cover for the fire-wall having depending flanges overlapping the free edge of the flashing, flexible metal cleats secured to the top cover, extending beneath the flanged portion thereof and the flashing, and secured to the roof at points removed from the wall, and a roofing material overlying the roof and portion of the flashing lying thereon.

In testimony whereof I affix my signature in the presence of two witnesses.

WILLIAM R. ROSE.
